UNITED STATES PATENT OFFICE.

JONATHAN LEE KNIGHT, OF KANSAS CITY, MISSOURI.

DESIGN FOR A CALENDAR-BLANK.

No. 38,938.

Specification for Design.

Patented Dec. 10, 1907.

Application filed August 19, 1907. Serial No. 389,304. Term of patent 3½ years.

To all whom it may concern:

Be it known that I, JONATHAN LEE KNIGHT, a citizen of the United States, residing at Kansas City, in the county of Jackson and State of Missouri, have invented a new, original, and ornamental Design for a Calendar-Blank, of which the following is a specification, reference being had to the accompanying drawing, forming part thereof.

The figure is a plan view of a calendar blank showing my design.

I claim

The ornamental design for a calendar blank as shown.

JONATHAN LEE KNIGHT.
